UNITED STATES PATENT OFFICE.

FREDERIC ALONZO MORLEY, OF BROOKLYN, NEW YORK.

MOUTH-FLUTE.

1,341,860.

Specification of Letters Patent. Patented June 1, 1920.

Application filed February 19, 1919. Serial No. 278,064.

To all whom it may concern:

Be it known that I, FREDERIC ALONZO MORLEY, citizen of the United States, and resident of the borough of Brooklyn, county 5 of Kings, city and State of New York, have invented certain new and useful Improvements in Mouth-Flutes, of which the following is a specification.

My invention relates generally to flutes 10 and more particularly to an improvement in mouth flutes in which tones are produced by the modulation of the breath, the same as tones are produced in natural whistling by the mouth.

15 The invention has four objects, first, to provide a mouth flute in which tunes and melodies can be produced by the modulation of the breath; second, to provide means by which musical notes and tones can be 20 made by the manipulation of the tongue; third, to provide means by which musical notes and tones can be produced and controlled by the manipulation of the lip; and, fourth, to provide a mouth flute by which 25 any one able to whistle a tune or melody can execute the same tune or melody in an artistic manner with trills, variations, and embellishments.

The following is what I consider a good 30 means of carrying out this invention, and the accompanying drawings should be referred to for a complete understanding of the specification which follows:—

In the drawing:—

35 Figure 1 is a top view of the device. Fig. 2 is a longitudinal sectional view taken on the line 2—2 of Fig. 1. Fig. 3 is a horizontal sectional view taken on the line 3—3 of Fig. 2. 40 Fig. 4 is a transverse section on the line 4—4 of Fig. 1. Fig. 5 is a top view of a modified form of the device.

45 Fig. 6 is a transverse sectional view illustrating a modified contour which may be given the device.

Similar reference numerals indicate like parts in all of the figures where they appear.

The shell or casing 1, of an oblong and 50 tapering form in top view constitutes the body of the device and may be of substantially rectangular shape in cross section as shown in Fig. 4. This shell incloses a tone or sound chamber 2.

55 The shell or casing 1 is provided, on the rear portion of its top face, with a smaller

supplementary shell or casing 3, which as shown is parallel to and spaced slightly apart therefrom, and is open at both ends and forms a supplementary chamber or compartment 3' for the passage of breath or wind from the mouth to an opening 4, which is in the form of a transverse slot in the top wall of the casing 1 located at the forward end of the supplementary shell 3. 60

Formed in the top wall of the casing 1, a short distance in front of the opening 4 is a trill hole 5 for the purpose of trilling or making variation by means of trilling or manipulating the finger in a rapid and vi- 70

bratory manner. The bottom wall of the casing 1 is formed at its rear end with a tapering recess 6, this recess corresponding substantially in position, as seen in plan view, with the supplementary shell 3, although being slightly narrower than the latter and terminating short of the forward end thereof. 75

The side walls of the casing 1 may incline downwardly and forwardly at their rear ends as shown at 7, while the top wall preferably extends in an overhang 8 which may have a convex rear edge as shown.

The modified form of flute shown in Fig. 5 is the same as that already described except that the body or casing 1 has an extension 11 provided with finger holes 12. 85

In Fig. 6, I have indicated how the body or casing 1 may be given an oval form in transverse section. 90

To operate the flute the wide end is put in the mouth with the supplementary casing 3 uppermost, or toward the roof of the mouth. The tongue is placed in the sound chamber 2, and the under lip is protruded so 95 as to completely cover the recess or opening 6 in the under side of the shell 1. When the tongue is at the extreme wide end of the shell 1, and the lip entirely covers the opening 6 in the bottom thereof, the lowest note 100 or tone can be produced by expelling the breath or wind through the chamber or channel 3'. As the tongue is extended forward toward the opening 4, the higher tones 105 can be produced, and at each and every point of the roof of the chamber 2, in which the tongue may be held, several notes can be produced by the modulation of the breath. When the lip is drawn backward so as to uncover the opening in the under side of the 110 shell 1, the higher notes can be produced in proportion to the drawing back of the lip,

and at each point at which the lip is drawn back, several or more notes or tones can be produced by the modulation of the breath expelled through the chamber or channel 3'.

5 At each point at which sound can be produced, trilling can be produced by vibrating or trembling the finger on the trill hole 5.

It will be understood that modifications may be made within the scope of the appended claims without departing from the principle or sacrificing the advantages of the invention.

Having carefully and fully described my invention what I claim and desire to secure 15 by Letters Patent is:—

1. A device of the class described having a casing adapted to be inserted in the mouth and receive the tongue of the user therein, and a supplementary casing extending from 20 the inner end to a point intermediate the ends of the first named casing and on one side thereof forming a wind passage.

2. A device of the class described having a casing adapted to be inserted in the mouth 25 and receive the tongue of the user therein, a supplementary casing on one side thereof forming a wind passage, and an opening formed in the first named casing adjacent the front end of said supplementary casing.

3. A device of the class described having a casing adapted to be inserted in the mouth and receive the tongue of the user therein, a supplementary casing on one side thereof forming a wind passage and an opening 35 formed in the main casing adjacent the front end of said supplementary casing, and a trill hole formed in front of said opening.

4. A device of the class described having a casing adapted to be inserted in the mouth 40 and receive the tongue of the user therein, and a supplementary casing of less length than the main casing on one side thereof forming a wind passage, said main casing having a recess in the rear portion of the 45 opposite side thereof.

5. A device of the class described having a casing adapted to be inserted in the mouth and receive the tongue of the user therein, a supplementary casing of less length than 50 the main casing on one side thereof forming a wind passage, a recess in the rear portion of the opposite side of said main casing, an

opening formed in the main casing adjacent the front end of said supplementary casing and a trill hole formed in front of said 55 opening.

6. A device of the class described having a casing of oblong tapering form adapted to be inserted in the mouth and receive the tongue of the user therein, a supplementary 60 casing of less length than the main casing on one side thereof forming a wind passage, a recess in the rear portion of the opposite side of said main casing, an opening formed in the main casing adjacent the front end of 65 said supplementary casing and a trill hole formed in the wall of the main casing carrying a supplemental casing and in front of said opening.

7. A device of the class described having a casing of oblong tapering form adapted to be inserted in the mouth and receive the tongue of the user therein, a supplementary casing of less length than the main casing 70 on one side thereof forming a wind passage, a recess in the rear portion of the opposite side of said main casing, an opening formed in the main casing adjacent the front end of 75 said supplementary casing and a trill hole formed in the main casing in front of said 80 opening, said recess and said supplementary casing tapering in correspondence to the main casing.

8. A device of the class described having a casing of oblong tapering form adapted to 85 be inserted in the mouth and receive the tongue of the user therein, a supplementary casing of less length than main casing on one side thereof forming a wind passage, a recess in the rear portion of the opposite side 90 of said main casing, an opening formed in the main casing adjacent the front end of said supplementary casing and a trill hole formed in the main casing in front of said opening, said recess and said supplementary 95 casing tapering in correspondence to and an extension on the top wall of the main casing.

Signed at New York city, county and State of New York, this 15th day of Feb., 1919.

FREDERIC ALONZO MORLEY.

Witness:

GEO. D. MOFFAT.
